UNITED STATES PATENT OFFICE.

IRVING A. PETERS, OF CHICAGO, ILLINOIS, ASSIGNOR TO THE PYLE-NATIONAL COMPANY, OF CHICAGO, ILLINOIS, A CORPORATION OF NEW JERSEY.

FLAG HOLDER AND CLASSIFICATION LIGHT STAND.

Application filed August 13, 1927. Serial No. 212,648.

My invention relates to improvements in flag stand and support for running and classification lights for railroads and the like. It has for one object to provide a new and improved flag stand which can carry both the light and the flag simultaneously and wherein the light stand may be wired for electric lights. Other objects will appear from time to time in the specification and claims.

10 My invention is illustrated more or less diagrammatically in the accompanying drawings, wherein—

Figure 1 is a detail fragmentary front view of a locomotive showing my device in place;

15 Figure 2 is a side elevation similar to Figure 1;

Figure 3 is a detail side elevation of the stand showing the light and flag staff in place;

20 Figure 4 is a view of the stand taken in the direction of the arrow in Figure 3 with lamp and connections removed;

Figure 5 is a section along the line 5—5 of Figure 4;

25 Figure 6 is a section along the line 6—6 of Figure 5;

Figure 7 is a plan view of the parts shown in Figure 5.

Like parts are indicated by like characters

30 throughout the specification and drawings.

My combined lamp and flag stand is adapted to be mounted on the bolster thereby being at a point down low where it is exposed to be struck and damaged and therefore the

35 assembly must be a distinctly rigid and well supported one. The stand comprises the hollow casing A adapted to be mounted on a

locomotive bolster A¹. This casing is flanged at its lower end as indicated at A² and is pro-

40 vided with a central boss A³ adapted to penetrate in the recess cut in the upper surface of the bolster A¹. A⁴ is a bolt extending down through the bottom of the stand and the bolster, the nut to hold it in place being not

45 here shown. The flange surrounding the base of the lamp stand is partly circular as indicated at A⁵ but straight along one side as indicated at A⁶ and at this point the flange

50 has in its under surface a transverse recess or channel A⁷ slightly reduced by the wall A⁸ at either end. This channel is closed along

its underside by the bolster itself and communicated with an upwardly extending conductor passage A⁹ cast integral with the

stand but separated from the hollow interior 55 thereof.

The passage A⁹ terminates in a connector socket B, the axis of this socket being downwardly inclined as indicated. The socket is cast integral with the lamp stand and has 60 on its upper side an over-hanging finger B¹ which is associated with a spring latch finger B² held in place by a screw B³ and having a latch portion B⁴ adapted to hold a contact plug in place.

65 The upper closed portion of the stand is oblong as disclosed in Figure 7 and contains a flag pole socket C and a rectangular shaped lamp holding socket C¹ in which is shown in Figures 3 and 5 for the purpose of 70 illustration, a lamp supporting arm C². It will be noted that this arm when it slides down into the socket C¹ is supported at a point removed from the socket by the abutment C³ whereby the lamp base C¹² with the 75 lamp C¹³ thereon will be held in firm and fixed position.

The lamp itself is a standard type and any suitable lamp may be used so no further description of the lamp need be given at this 80 time. Suffice it to say there projects from the bottom of the lamp a flexible conductor C⁴ which projects in a push plug C⁵ having a ring C⁶ adapted to be engaged by the latch B⁴ to hold the plug in place. This push 85 plug has on it two spring contact fingers C⁷ C⁷ adapted to engage cylindrical contacts C⁸ in the base plug C⁹. Conductors C¹⁰ extend in through the opening A⁷, passage A⁹ to the base plug being supplied with electric current in any suitable manner.

90 In order to take care of the case where electric lights are not desired or in order to take care of a situation where a different type of lamp bracket is used, there is disposed in 95 the wall of the stand a socket D enlarged at the top as at D¹ and having tapering walls as at D² whereby the ordinary type of oil lamp may be engaged with the socket and held in position thereon. It will be noted that the relation of the parts is such that if it is desired to have both the oil lamp and the electric lamp carried by the stand at the same time, this may be done. The same is 100 equally true of the flag staff D³ which is shown engaged in the socket C without in any way interfering with the operation or support of either of the lamps.

I claim:

1. A flag holder and classification light stand for locomotives and the like comprising a flanged upwardly extending hollow bracket, a lamp supporting socket and a flag staff socket at the upper end thereof, a housing integral with and projecting outwardly from one wall thereof, and a base plug contained therein, an integral conduit adapted to 10 conduct wires from the bottom of the support to the socket.

2. A flag holder and classification light stand for locomotives and the like comprising a flanged upwardly extending hollow bracket, a lamp supporting socket and a flag staff socket at the upper end thereof, a housing integral with and projecting outwardly from one wall thereof, and a base plug contained therein, an integral conduit adapted 15 to conduct wires from the bottom of the support to the socket, the axis of the base plug and socket being outwardly inclined.

3. A flag holder and classification light stand for locomotives and the like comprising a flanged upwardly extending hollow bracket, a lamp supporting socket and a flag staff socket at the upper end thereof, a transverse wire containing conduit in the flange, a passage in the wall of the support extending 20 upwardly from the transverse conduit, a cylindrical socket integral with the support communicating with such passage and having its axis downwardly inclined.

4. A flag holder and classification light stand for locomotives and the like comprising 25

a flanged upwardly extending hollow bracket, a lamp supporting socket and a flag staff socket at the upper end thereof, a transverse wire containing conduit in the flange, a passage in the wall of the support extending 40 upwardly from the transverse conduit, a cylindrical socket integral with the support communicating with such passage and having its axis downwardly inclined, a lip overhanging the open mouth of the socket 45 and a holding spring latch contained within the socket beneath the lip.

5. A flag holder and classification light stand for locomotives and the like comprising a flanged upwardly extending hollow bracket, a lamp supporting socket and a flag staff socket at the upper end thereof, a transverse wire containing conduit in the flange, a passage in the wall of the support extending 50 upwardly from the transverse conduit, a cylindrical socket integral with the support communicating with such passage and having its axis downwardly inclined, the lamp supporting socket being located above 55 the cylindrical socket, a base plug contained in the cylindrical socket, a lamp and bracket engaging the lamp socket and a conductor having at one end a contact plug adapted to engage the base socket and communicating at the other end with the lamp. 60 65

Signed at Chicago county of Cook and State of Illinois, this 10th day of August, 1927.

IRVING A. PETERS.
